UNITED STATES PATENT OFFICE.

DONALD M. MCLEAN, OF BOSTON, MASSACHUSETTS.

METHOD OF MOLDING KETTLES, &c., WITH HINGE-PINS.

SPECIFICATION forming part of Letters Patent No. 357,778, dated February 15, 1887.

Application filed December 9, 1885. Serial No. 185,198. (No model.)

To all whom it may concern:

Be it known that I, DONALD M. MCLEAN, a citizen of the United States, residing at Boston, in the county of Suffolk and State of Massachusetts, have invented a new and useful method of producing metal castings wherever applicable by piercing the ears or sides of the pattern to receive a pin or pins, or to cast the same integrally with the body of the vessel; and I do hereby declare that the following is a full, clear, and exact description of my invention, which will enable others skilled in the art to which it appertains to make and use the same.

15 My invention relates to improvements in all classes of hollow wares produced from cast metals which are to be provided with hinged covers or lids, and in the method of attaining this result.

20 My invention therefore consists in the novel manner of manipulating a two-part mold to attain the result hereinafter shown, which consists in uniting the hinge-pin to the ears or projecting lugs of the vessel, making the former integral with the latter at one operation, or, where desirable, permitting the molten metal to form a hinge-pin where the dimensions of said pin will insure sufficient strength to sustain the cover or lid of the larger or weightier 25 class of castings. Accomplishing this result by my improved method of forming the lugs of the mold obviates the laborious, slow, and expensive process of drilling as heretofore practiced, and avoids the expense consequent 30 from the loss of completed castings, which, during the process of casting, have sustained a change of crystallization and become chilled to a degree which renders them impervious to drilling.

35 My improvement in detail is hereinafter specifically described, and illustrated in the accompanying drawings, forming a part of this specification, in which—

Figure 1 exhibits a view in perspective of a 40 "two-part" tea-kettle flask prepared to receive the molten metal. Fig. 2 is a vertical transverse central section in perspective of the cope of said flask supported on a molder's block and containing the lower half of a tea-kettle pattern embedded in sand. Fig. 3 illustrates a perspective view in section, said flask and pattern being inverted to receive the up-

per part of the pattern and flask. Fig. 4 indicates a perspective view in section, wherein said upper half of the pattern and flask with 55 the sand have been added. Fig. 5 is a perspective of the drag of the flask containing the sand-mold with the pattern removed. Fig. 6 embraces a view in perspective of the lower part of said flask containing the "core" and 60 the bottom of the pattern still embedded in the sand. Fig. 7 indicates a top plan of an empty flask resting upon the block. Fig. 8 is a perspective view of the devices supporting the core of the mold in the flask. Fig. 9 illustrates a portion of the pattern bearing the 65 lugs or ears, which are pierced to receive a hinge-pin. Fig. 10 is a portion of a casting therefrom sustaining one hinge-pin, and Fig. 11 is a similar view bearing two short pins. 70 Fig. 12 shows the product.

To carry my invention into effect, I proceed in the consecutive order illustrated in the several annexed views, commencing with Fig. 2 as the—

75 First operation, wherein the lower half or "bottom" of a tea-kettle pattern, A, is placed upon the "mold-block" B in an inverted position: The lower portion of the flask or "drag" C is adjusted to conform with said pattern, and the intervening space is then filled with "molding-clay" or sand properly "tempered" and compacted with the "tamping-iron" until the cavity is uniformly filled. The "gate" D is now formed at the bottom of the drag to receive 80 the molten metal by forcing the "sprue" E down upon the pattern-bottom, where it remains until the mold is completed. The founder now inverts the drag C, whence it assumes the position as in Fig. 3, and the flask 85 is ready for the—

Second operation: The "parting-sand" is strewn over the surface, and the top half of the pattern or "breast" F is carefully adjusted upon the "set" pattern, and the upper portion 90 or cope of the flask G is arranged carefully by means of the offsets H and flask-pins I upon the rims of the drag and cope, respectively, as appears in Fig. 3. The interior of the pattern is partially filled with the sand and compacted 95 by hand. At this stage of proceeding the "anchor" J is inserted within the pattern, the "crown" K resting about midway the depth of the drag, with the "shank" L protruding

above the top of the cope. The pin M or pins M' are now inserted through the holes N in the ears O of the pattern, and the interior of said pattern is filled and tamped compactly with sand to a level with the rim, the sand being also packed on the outside of the pattern between the ears O O, and around said pin M, thus forming a small projecting block of sand on the core S, pierced by the pin M, as shown in Fig. 6. Parting-sand is now applied to the top of said core, including the aforesaid projecting block of sand, and the cope is tamped. The anchor-stock P is adjusted over the shank L and secured by the inclined key Q ready for the—

Third operation: This consists in removing the cope—after ventilating the “matrix” and removing the key and stock—as appears in Figs. 5 and 6, wherein said cope is lifted from the pattern, the pin or pins withdrawn, and the breast of the pattern removed to expose the matrix R. The “pounce-bag” is now brought into requisition, containing a composition of plumbago and charcoal-dust, which is pounced upon the “nowel” or core S, to harden the mold and facilitate the flow of the liquid metal, after which said cope G is readjusted upon the drag C, the pin or pins meanwhile being replaced in the mold, when desired to form said pin or pins integral with the casting, or left out if it is desired to form a cast pin by allowing the molten metal to

flow through said holes in the mold, as the process may be elected. The stock and key being replaced, the flask is once more inverted, and the drag and mold are lifted to expose and to permit the removal of the lower half of the pattern and the use of the pounce, as in the manner aforesaid. Readjusting the parts of the flask and the removal of the sprue completes the mold.

Having described the operation and construction of my improved invention, what I desire to secure by Letters Patent of the United States, and claim, is—

The process of forming a mold to make an article having ears with pintles cast therein, consisting in molding the drag, molding the core inside of a pattern having on its exterior two pierced lugs, inserting a pin or pins through the pierced lugs of the pattern, molding between the lugs of the pattern and around the pin or pins a pierced lug integral with the core, completing the remainder of the mold, withdrawing the cope, withdrawing the pin or pins from the molded lug, withdrawing the pattern, replacing the pin or pins, and reassembling the mold, all as described.

In witness whereof I have signed this specification in presence of two attesting witnesses.

DONALD M. MCLEAN.
